UNITED STATES PATENT OFFICE.

JOHN McMYLER, OF CLEVELAND, OHIO, ASSIGNOR TO THE McMYLER INTERSTATE COMPANY, OF BEDFORD, OHIO, A CORPORATION OF OHIO.

CAR-HANDLING SYSTEM.

1,240,466.

Specification of Letters Patent. Patented Sept. 18, 1917.

Application filed February 11, 1915. Serial No. 7,633.

To all whom it may concern:

Be it known that I, JOHN McMYLER, a citizen of the United States, residing at Cleveland, in the county of Cuyahoga and State of Ohio, have invented a certain new and useful Improvement in Car-Handling Systems, of which the following is a full, clear, and exact description.

This invention relates to car handling systems and has for its object to provide an improved system for handling or transferring cars adapted to be employed in connection with some type of car handling apparatus, such as car dumpers.

At the present time with practically all car dumpers, the cars are brought separately up to the car dumper by a haulage car traveling along a narrow gage track, extending from a point a short distance from the car dumper up an inclined approach to the dumper cradle. The loaded cars are usually allowed to drift or run by gravity from an elevated track down an incline to the base of the inclined approach to the car dumper or to the point at which they are picked up by the haulage car.

This haulage system and method of handling the cars is satisfactory in many respects, but has numerous disadvantages. For example, the inclined approaches are rather expensive to build, requiring elevated tracks and fills. Additionally, a number of men are required to handle the cars,—usually one man riding on each car as the same drifts down the incline to the point at which it is adapted to be picked up by the haulage car. Furthermore, with many haulage systems operating on the principle above stated, there is a considerable element of risk in the shifting of the cars, due to the fact that it is rather difficult to control the cars as they are passing down the incline, and it is sometimes the case that collisions occur if a car cannot be stopped on the incline.

The above and other disadvantages of prior construction are overcome by my invention, which may be briefly summarized as consisting in certain novel details of construction and combinations and arrangements of parts which will be described in the specification and set forth in the appended claims.

In the accompanying sheet of drawings, showing one embodiment of my invention, Figure 1 is a plan view of the major por-

tion of the car handling apparatus, many of the parts being shown conventionally; Fig. 2 is a sectional view substantially along the line 2—2 of Fig. 1, the transfer table and haulage car thereon being shown in elevation; Fig. 3 is a sectional view substantially along the line 3—3 of Fig. 1, looking in the direction indicated by the arrows; Fig. 4 is a sectional view substantially along a line 4—4 of Fig. 1, looking in the direction indicated by the arrows.

The car handling apparatus includes one or more tracks 10 for the loaded cars, there being any number of the tracks, four of the same being here shown. These tracks may all be built on level ground, no inclined or elevated track portions being required, as the loaded cars are not intended to pass along any portion of the tracks by gravity.

At 12 is shown a car dumper which in this case is located laterally and close to the tracks 10. This car dumper usually consists of frame-work or tower 13 having a cradle 14, which is adapted to receive the cars one at a time, and is adapted to be elevated and then tilted so as to dump the contents of a car into a suitable chute, the cradle having tracks upon which the car may be run.

Located at the ends of the tracks 10 and adjacent one end of the car dumper 12 is a pit 15 having at the bottom a series of rails 16 extending at right angles to the tracks 10 and car dumper 12. Traveling over these rails in the pit is a so-called transfer table 17. This transfer table which is adapted to be shifted laterally so as to convey loaded cars from any one of the tracks 10 to the dumper, is provided with a track 18 which is on the same level with the tracks 10 and with the track on the cradle 14 of the car dumper when the latter is in its normal lowered position.

Adapted to travel back and forth on the track 18 of the transfer table is a haulage car 19 having a forwardly projecting arm 20, provided at its outer end with a car coupler, and of sufficient length that a car located on any one of the tracks 10 at a predetermined distance from the pit can be engaged and coupled to the haulage car, so that it can be drawn onto the transfer table by the latter. Furthermore, the length of this arm 20 is such that after the transfer table has been brought in alinement with 110

the car dumper the haulage car may push a loaded car from the transfer table onto the cradle of the car dumper and center the car on the cradle.

5 The haulage car may be shifted back and forth over the track of the transfer table by any suitable mechanism, but in this instance it is pulled back and forth by a cable 21 which is wound a suitable number of times

10 around a drum 22, which may be driven by any suitable motor or engine, and is located in an inclosure 23 erected on one end of the transfer table. This haulage rope 21 is connected at one end to the rear end of the haulage car and thence extends rearwardly around the drum, and thence forwardly beneath the top of the transfer table about a sheave 24 at the forward end of the transfer table, and after passing about this sheave

15 is attached to the lower rear side of the haulage car at 25. With this arrangement the haulage car can be moved from a point adjacent the inclosure 23 to the opposite end of the transfer table with the coupler arm 20 projecting beyond the transfer table, as

20 shown by full lines in Fig. 2.

25 Any suitable mechanism may be employed for shifting the transfer table laterally along the rails 16. The track wheels of the

30 turntable may be geared to a motor contained within the inclosure 23, or within the operator's inclosure 26 located at the forward end of the transfer table and at one side of the same, or, this transfer table may

35 be shifted back and forth along the tracks by a suitable motor or engine driven drum and by cables passing about sheaves 30 located in the lower part of the pit.

40 The mode of operation of the car handling apparatus, including the parts previously described and other parts to be referred to, is as follows:

45 Any one or all of the tracks 10 may be provided with loaded cars, the cars on each track being left coupled, and the foremost car standing close to the pit in substantially the position shown in Fig. 2. The transfer table is shifted laterally along the tracks 16 until the track 18 on the table is in line with

50 one of the tracks 10 from which the cars are to be taken; then the haulage car is run forwardly and the coupler arm is coupled to the adjacent car on the track and then the haulage car is moved toward the opposite

55 end of the transfer table, pulling forwardly the entire string of cars on the track, and pulling one of the cars onto the track of the transfer table, as shown by dotted lines in Fig. 2. When the second car from the

60 end of the string is in substantially the position previously occupied by the first car, as shown in Fig. 2, the foremost car now standing partially on the transfer table is uncoupled from the next car, whereupon the

65 uncoupled car may now be pulled entirely

upon the transfer table. Thence the transfer table is moved laterally to the car dumper, and when it is in alignment with the latter the car is pushed by the haulage car from a transfer table onto the cradle of the car dumper, and is left in central position thereon. Thence, while the car on the car dumper is being elevated and dumped, and thence lowered, the transfer table is shifted back to the same track 10 or to some other track 10 from which the cars are to be taken, and the operation is repeated. After the car has been emptied in the dumper it passes away from the car dumper on a so-called empty track, a portion of which is shown at

70 the right hand end of the car dumper. The empty car may be pushed from the cradle by the following loaded car as the latter is being pushed onto the cradle by the haulage car.

75

80 The car dumper may discharge the contents of loaded cars into any suitable receiving receptacle or container. In many instances it is arranged to discharge material directly into boats. In other instances it discharges into cars or receivers in the form of buckets. In this case the car dumper is adapted to discharge directly into buckets 32 mounted on flat cars 33 running along a track 34 which extends from the car 95 dumper past the pit and out onto a dock 35, where suitable apparatus will be provided for picking up the buckets and dumping the contents thereof into a vessel, a portion of which is shown at 36. However, that part of the system for receiving and handling material discharged by the car dumper constitutes no part of the present invention and may be otherwise arranged than here shown.

90

95 The mode of operation of the car handling apparatus by which the loaded cars are brought from the loaded tracks and are delivered one at a time on the car dumper, the cars may be handled very rapidly and with minimum danger and low cost of operation especially as far as the number of operators is concerned. Furthermore, as previously stated, by avoiding the necessity for the inclined or elevated tracks the first cost of the apparatus and track 110 layout is less than that of the haulage systems and track layouts commonly employed at the present time with car dumpers.

115

120 Having thus described my invention, what I claim is:

1. In a car handling system, one or more tracks for loaded cars, a car receiving device, a traveling platform of sufficient length to receive a car for transferring cars from said track or tracks to the car receiving device and a car haulage device located on the platform and movable back and forth along the same.

2. In a car handling system, one or more tracks for loaded cars, a car receiving de-

vice and a traveling platform of sufficient length to receive a car for transferring cars from said track or tracks to the car receiving device, and means on said platform for shifting the cars.

3. In a car handling system, one or more tracks for loaded cars, a car receiving device, a traveling platform of sufficient length to receive a car for transferring cars from 10 said track or tracks to the car receiving device, and a haulage car on the platform for moving cars on to and from the platform.

4. In a car haulage system, one or more tracks for loaded cars, a car receiving device 15 displaced laterally with respect to said track or tracks, and a transfer platform movable back and forth between the track or tracks and the car receiving device for conveying cars from the former to the latter.

20 5. In a car haulage system, one or more tracks for loaded cars, a car receiving device displaced laterally with respect to said track or tracks, a transfer platform movable back and forth between the track or 25 tracks and the car receiving device for conveying cars from the former to the latter, and means on said platform for moving the cars.

6. In a car haulage system, one or more 30 tracks for loaded cars, a car receiving device displaced laterally with respect to said track or tracks, a transfer platform movable back and forth between the track or tracks and the car receiving device for conveying 35 cars from the former to the latter, and a haulage car on the platform for drawing cars from the track or tracks on to the platform and for pushing cars from the platform onto said receiving device.

40 7. In a car haulage system, one or more tracks for loaded cars, a car receiving device displaced laterally with respect to said track or tracks, a transfer platform movable

back and forth between the track or tracks and the car receiving device for conveying 45 cars from the former to the latter, and a haulage car on the platform for drawing cars from the track or tracks on to the platform and for pushing cars from the platform onto said receiving device, said haulage 50 car having a forwardly projecting arm adapted to extend beyond the platform.

8. In a haulage system, one or more tracks for loaded cars, a car dumper arranged at the side of said track or tracks, a plurality 55 of rails extending substantially at right angles to said track or tracks and car dumper, a transfer platform movable over said rails and having a track adapted to be brought in alinement with each of said first named 60 tracks and with the car dumper, a haulage car mounted to move back and forth on the track of the said platform and having means adapted to be coupled to a car to pull the same from one of said tracks onto the platform and to push the same from the latter into the car dumper.

9. In a car haulage system, a plurality of tracks adapted to be supplied with loaded cars, a car dumper at the side of said tracks, 70 a pit arranged adjacent the ends of said tracks and the end of the car dumper, a transfer platform movable back and forth in said pit and having means for drawing a car from any one of said tracks onto the table 75 and for pushing the car from the platform into the car dumper when the table is shifted laterally from the track into alinement with the car dumper.

In testimony whereof, I hereunto affix my 80 signature in the presence of two witnesses.

JOHN McMYLER.
